UNITED STATES PATENT OFFICE.

WILFRED L. BOON, OF NORTH ATTLEBORO, MASSACHUSETTS.

T-SQUARE.

1,419,354.

Specification of Letters Patent. Patented June 13, 1922.

Application filed July 19, 1920. Serial No. 397,289.

To all whom it may concern:

Be it known that I, WILFRED L. Boon, a subject of the King of Great Britain, residing at North Attleboro, in the county of 5 Bristol and State of Massachusetts, have invented certain new and useful Improvements in T-Squares, of which the following is a specification.

This invention relates to improvements in 10 T-squares used more particularly on drawing boards, and has for its object to provide a square of this character with a gripping jaw slidably mounted on the blade thereof to cooperate with the working edge 15 of the edge of the head of the square to automatically grip the board between them and so hold the square in adjusted position on the board.

The nature and advantages of the invention 20 will be better understood when the following detail description is taken in connection with the accompanying drawings, the invention residing in the combination and arrangement of parts as claimed.

25 In the drawings forming part of this specification, like numerals of reference indicate similar parts in the several views and wherein:—

Figure 1 is a plan view of my improved 30 square showing the gripping jaw as binding the square to a drawing board shown in dotted lines.

Figure 2 is an edge view of the square partly in section, shown as gripping a board 35 which is illustrated in dotted lines.

Figure 3 is a section through the square showing the jaw with its binding screw engaging the connector member.

It is found in practice much easier to 40 work upon a drafting board which is set on an incline, and, ordinarily, to operate a T-square on such a board it must be connected thereto by means of an elaborate arrangement of wires and pulleys so as to 45 hold it square in adjusted position when moved up or down over the surface of a board, but such an arrangement is found quite expensive and is not practicable to be applied to all boards.

50 My improved attachment is adapted to be readily applied to any T-square and by its use a T-square of the ordinary type may be applied to any board and caused to stay in any adjusted position on the board regardless of its inclination when moved up or down over its face.

The following is a detail description of one means by which this result may be accomplished:—

With reference to the drawings, 10 designates the head of an ordinary T-square, the inner or working edge of which is adapted to engage and slide on one edge of the drawing board 12.

To this head member is secured the ordinary blade 13 of the square, the length of which should be slightly greater than the width of the board to which the square is applied.

On this blade I have slidably mounted a 70 gripping member or jaw 14 which comprises an upper plate 15 and a lower plate 16 riveted together through the spacers 17 and these plates are separated sufficiently to provide a space between them sufficient 75 to receive the blade.

On the upper plate 15, I have secured a looped-shaped member 18 through which the connector wire, presently described, passes and through the upper wall of which I have 80 threaded a binding screw 19 to grip the wire and hold this jaw in adjusted position thereon. To the lower plate 16 of this bar I have secured a binding finger 20 which extends downwardly therefrom to engage the edge 85 22 of the drafting board, which is opposite that engaged by the working edge 11 of the head.

On the outer edge of this head I have mounted a spring-tension lever 23 which is 90 secured at one end to the edge of the head by means of the clip 24. This lever is preferably constructed of a strip of resilient sheet metal having its operating end raised a suitable distance from the edge of the 95 head, and to this lever is secured one end of the connector wire 21 which leads through the guide 25 and through the member 18 of the jaw, its opposite end being connected to the coiled spring 26 which is considerably 100 lighter in tension than the spring in the lever 23. This light spring 26 is preferably housed in the casing 27 secured near the outer end of the blade.

In order to facilitate operating this T- 105 square, I have attached a thumb clip 28 to its head portion so that in moving the square up and down over the face of the drafting board it is only necessary to engage the clip 28 with the thumb while the finger presses 110 inwardly on the tension lever 23 which pressure relieves the tension on the wire con-

necter 21 permitting the lighter spring 26 to draw the clamping jaw from gripping engagement with the edge 22 of the board; then the T-square may be readily moved up 5 or down over the surface of the board and when positioned the grip of the hand on the lever 23 is released, permitting this lever to move outwardly and so overcome the tension on spring 26 causing the jaw to engage the 10 edge 33 of the board, which cooperating with the working edge 11 of the T-square, grips the board between them and holds the square in adjusted position thereon.

In some instances the difference between 15 the spring members 23 and 26 is so slight that the T-square may be easily moved in any adjusted working position without operating the lever 23.

The device is extremely simple and practical in construction and effective in its 20 operation.

The foregoing description is directed solely towards the construction illustrated, but I desire it to be understood that I reserve the privilege of resorting to all the 25 mechanical changes to which the device is susceptible, the invention being defined and limited only by the terms of the appended claims.

30 I claim:

1. A T-square for drawing boards comprising a blade with a cross-head connected thereto at one end, a gripping jaw adjustably mounted on said blade, a spring-tension 35 lever on said head, a light spring at the opposite end of the blade, a connector extending from said lever to said light spring, and said jaw being adjustably connected to said connector, whereby said lever spring over- 40 comes the tension of said light spring to cause said jaw to cooperate with said head to grip the board between them.

2. A T-square for drawing boards comprising a blade with a cross-head connected 45 thereto, a grip jaw slidably mounted on the blade, a tension means secured at the end portions of the blade, the tension means at the cross-head end of the blade being stronger than the other, a flexible connector having its ends attached to said tension means at each end of said blade, means whereby 50 said jaw may be adjustably connected to

said connector at any point along its length causing the jaw to cooperate with the working edge of the cross-head to grip the board 55 between them.

3. A T-square for drawing boards comprising a blade having a cross-head connected thereto at one end, a gripping jaw having a slot therein for slidably receiving 60 said blade, a compressible means at the cross-head end of the blade, a tension spring secured at the other end of the blade, a flexible connector connecting said spring and compressible means, said compressible 65 means normally holding said connector taut, said jaw having a passage therein through which said connector extends, and a binding screw threaded in said jaw and extending in said passage for adjustably securing said 70 jaw to said connector along its length.

4. A T-square for drawing boards comprising a blade provided with a cross-head at one end thereof, a grip jaw slidably mounted on the blade, a spring tension lever 75 mounted on said cross-head and extending substantially longitudinally thereof, and means connecting said gripping jaw and said lever.

5. A T-square for drawing boards comprising a blade provided with a cross-head at one end thereof, a grip jaw slidably mounted on the blade, a spring tension lever mounted on said cross-head and extending substantially longitudinally thereof, means 85 connecting said gripping jaw and said lever, and a finger-grip at the cross-head end of the blade arranged in such relation to said lever so as to facilitate the operation of the lever for releasing tension on said jaw. 90

6. A T-square for drawing boards comprising a blade provided with a cross-head at one end thereof, a grip jaw slidably mounted on the blade, a spring tension lever mounted on said cross-head and extending 95 substantially longitudinally thereof, a lighter spring secured to the other end of the blade, a connector extending between the said lever and lighter spring and attached thereto, a means for adjustably connecting 100 said jaw to said connector along its length.

In testimony whereof I affix my signature.

WILFRED L. BOON.
